Foxboro Company, Foxboro, Mass., a corpora-
tion of Massachusetts

Application March 14, 1951, Serial No. 215,611

1 Claim. (Cl. 137—85)

1

This invention relates to instruments of the type used for recording, indicating, and/or controlling values of variable conditions such as temperature, pressure, flow, and the like.

It is particularly concerned with a pneumatic action device for use in such instruments.

Such instruments use condition sensing elements responsive to value changes in the variable conditions, and the response of the sensing element to the condition change is transmitted to an action device in the instrument for operating a recording, indicating, or control unit.

It is an object of this invention to provide a new and improved device of this nature.

The device of this invention is inexpensive, compact, and accurately effective with small forces, and is in the form of a balance arrangement which is productive of a pneumatic operating output force proportionally representative of the sensing element response to the variable condition change.

An illustrative embodiment of this invention is shown in the accompanying drawings, in which:

Figure I is a diagrammatic illustration of a nozzle and ball piston unit pneumatic device; and

Figure II shows the detail of the ball piston pneumatic unit.

The embodiment of this invention as shown in Figure I is an arrangement for controlling the temperature of a process.

As will be explained, temperature variations in the process are made to control an input to the process. This is done by translating movement produced by the response of a thermometer in the process into proportional pneumatic pressure for application to a valve in the input, and this translation is accomplished by a pneumatic action device, in this instance comprising a flapper unit, a nozzle, a ball piston pneumatic unit, and a pneumatic relay.

Referring to Figure I, at the lower left, a process tank is indicated at 10. Projecting into the tank 10 is a thermometer 11 for sensing temperature changes in the process. This thermometer may be of the common liquid filled type.

Connected to the thermometer 11 is a tube 12 through which the response to temperature variation is travelled to produce movement in a spiral Bourdon tube 13. Secured to the Bourdon tube to receive its movement, is a connector 14. This connector is secured to a lightweight flapper unit generally indicated at 15.

The portion of the flapper unit 15 to which the connector 14 is secured is in the form of a T as at 16, with the connector 14 secured thereto

2

at the base of the T. This T is mounted on a pivot 17 at the point of intersection of the upright and cross portions of the T. Thus a temperature variation in the tank 10 results in a pivotal movement of the T 16. This movement, or at least a part of it, depending upon the particular dimensions and configurations of the T 16 and the remainder of the structure, is transferred to the remainder of the flapper unit through engagement with a pin 18, extending through the cross portion of the T, generally parallel with the pivot 17. Several openings are located in the cross portion of the T, and the pin 18 may be placed in any one of them to vary the direction or degree of transfer of the motion of the T 16 to the remainder of the flapper unit.

The remainder of the flapper unit comprises two members 19 and 20 which are secured to each other to form a unitary structure. The member 19 is generally in the form of a W with its two outer legs and its base formed rigidly, and its center leg formed as a flat resilient member of substantially the same length as the outer legs. The member 20 is resilient and generally in the form of a triangle with a triangular central opening, a strip connection 21 extending from its base and an arm 22 on the strip connection, substantially parallel with the base of the triangle and with the cross portion of the previously mentioned T member 16 when the T is upright. The W member 19 and the triangle 20 are rigidly secured together along their bases, with the apex of the triangle overlying the upper end of the middle leg of the W, but somewhat short of the extremity thereof. Through the apex of the resilient triangle member 20 there is mounted an adjustment screw 23 which engages the resilient center leg of the W member 19. Thus more or less pressure may be adjustably exerted on the center leg of the W.

The W member 19 is pivotally mounted about an axis 24 which extends through the outer ends of the outer legs of the W 19 through mounting bosses 25. This axis 24 is perpendicular to the axis of the pivot 17 of the previously mentioned T member 16, and is parallel to the arm 22 on the triangle member 20.

Connection between the T member 16 and the remainder of the flapper unit is accomplished through the engagement of the pin 18 in the T member with the arm 22 on the triangle member 20. Thus a temperature variation in the process tank 10, within arranged limits results in a movement of the structure comprising the W member 19 and the triangle member 20, about the axis 24.

Associated with the flapper 15, and specifically with the resilient center leg of the W member 19, there is a pneumatic nozzle 26 and a pneumatic ball piston unit 27. This nozzle and piston are aimed at the center leg of the W member 19 in such a manner that pneumatic flow from the nozzle and force of the ball piston unit will be directed against the center leg of the W member, and movement of the flapper unit about the axis 24 releases or restricts pneumatic flow from the nozzle. The pneumatic flow from the nozzle 26 is minor so that the flow has no operative effect on the position of the center leg of the W member. Force from the ball piston unit 27 however, is used to move the center leg of the W member in opposition to its movement with respect to the nozzle 26 as obtained from a temperature variation in the process tank 10.

The nozzle 26 and the ball piston unit 27 are both connected to a pneumatic relay, generally indicated at 28. The construction and operation of this type of pneumatic relay is shown and described in my pending patent application for a Controller, filed August 21, 1946, Serial No. 692,102, now Patent No. 2,631,570 of March 17, 1953. Generally speaking there is a pneumatic path through the relay through which a substantial pneumatic operating pressure may be travelled. This path is opened or closed, partially or fully, through movement of a diaphragm, with the diaphragm movement controlled by a minor, or throttling, pneumatic pressure.

As shown in Figure I, the relay 28 is provided, at the top, with a pneumatic pressure input 29. The relay has a power chamber 30 and a secondary chamber 31, with the input pressure having unrestricted access to the power chamber 30 and restricted access to the secondary chamber 31 through a restrictor passage 32. These chambers are separated by a diaphragm 33, and the power chamber 30 is divided into two subchambers joined by a passage 34 axially perpendicularly aligned with the central portion of the diaphragm 33. The diaphragm carries a valve unit 35 which extends through the passage 34, being engaged in the power chamber by a spring 36 as an aid in closing the valve.

From the passage 32 between the subchambers of the power chamber 30 and extending into neither, there is an output passage 37. Thus, with the valve 35 open, an unrestricted pneumatic path is provided through the relay by way of the input 29, one of the subchambers of power chamber 30, chamber passage 34, and the output passage 37. At the bottom of the relay there is a passage from the power subchamber adjacent the diaphragm, as at 38, operable as a bleed to atmosphere.

Referring again to the nozzle 26, it is a pneumatic bleed nozzle and is connected by a tube 39 to the relay secondary chamber 31. Thus a minor pneumatic flow is provided from the nozzle 26 by way of the relay input 29 and the restrictor opening 32. The ball piston pneumatic unit 27 is connected by a tube 40 to the relay output passage 37 so as to be provided with a substantial pneumatic force when the relay valve 35 is open. Further, the relay output passage 37 is connected, as shown at the bottom of the drawing, to a pneumatic valve 41 in a pipe line 42 leading into the process tank 10. The temperature of the process in the tank 10 is controlled by a heating or cooling medium applied to the process through the pipe line 42, with this application controlled by the valve 41.

Referring to Figure II, it is simply a showing of the detail of the ball piston unit 27. It comprises a cylinder with an open outer end and a ball 45 smoothly fitted therein for movement along the axis of the cylinder. Engagement of the ball with the flapper resilient leg 19a as shown in dotted lines at 46 keeps the ball from leaving the piston unit and is the manner of applying the force from the relay 28 to the flapper unit resilient leg 19a.

In the operation of the device, the flapper unit 15 is arranged to tend to fall by gravity, about the axis 24, and toward the bleed nozzle 26. To set up an example, assume the arrangement shown in Figure I, and assume that the temperature in the process tank 10 is such that the flapper unit is supported by the pin 18 and that the resilient leg 19a is spaced from the bleed nozzle 26. Under all conditions, the free end of the flapper leg 19a is resting on the ball piston unit 27.

Under the above conditions, assume, further, a drop in temperature. The resulting action is that the pin 18 is moved downward, and under the action of gravity, the flapper unit 15 follows the pin 18 down, by movement about the flapper unit axis 24. Through this movement, the flapper resilient leg 19a approaches the bleed nozzle 26, gradually throttling off the pneumatic flow therefrom.

As this flow is restricted, pressure builds up in the relay 28 in the secondary chamber 31, resulting in movement of the diaphragm 33 and in opening the valve formed by the passage 34 and the valve unit 35. A pneumatic pressure from the power chamber 30 is thus introduced into the relay output passage 37 and into the ball piston unit 27.

This pressure in the ball piston unit is applied upwardly against the free end of the flapper unit 15 resilient leg 19a. This pressure, since it is applied, essentially, on the axis 24 of the flapper unit 15, has, for practical purposes, no effect on the movement of the flapper unit 15 about the axis 24. However, the ball piston pressure does act upon the resilient leg 19a and the resilient member 20. This action lifts the leg 19a from the bleed nozzle 26, or at least, resists the movement of the leg 19a toward the nozzle 26, that is, the downward movement caused by the downward pivoting of the flapper unit 15 as a whole. Thus a balance may be achieved at any position of the pin 18, within a given range.

The action is reversed under rising temperature conditions. As the flapper unit 15 is lifted about its pivot 24, the resilient leg 19a is lifted away from the bleed nozzle 26. The consequent increase of pneumatic flow from the nozzle 26 results in reduced pressure in the ball piston unit 27 and the resilient leg 19a through its resilience, tends to approach the nozzle 26, so a balance may again be achieved.

The force thus determined as that necessary from the ball piston unit to hold the flapper resilient leg in its position of balance, is the output force of the device, as applied through the relay output passage 37 to the pipe line valve 41. This output force is proportionally related to the Bourdon movement as produced by temperature changes in the process tank 10.

The ball piston unit 27 is so located in the particular structure shown as to provide intersection between the longitudinal axis of the unit 27 and the flapper unit pivot axis 24. The flapper unit resilient member 19a may thus pivot on the ball of the ball piston unit as the flapper unit is

pivoted about its axis 24, without varying the leverage factor on the flapper resilient member. Such a factor may be impressed on the resilient member as previously indicated herein, by adjustment of the screw 23.

The output force proportion referred to above is variable by changing the location of the nozzle 26 with respect to the flapper unit and with respect to the ball piston unit. In this instance the bleed nozzle tube 39 is flexible and the nozzle 26 may be adjusted toward or away from the ball piston unit 27. This adjustment is accomplished by movement of a sliding arm 43, as in Figure I, which is held in adjusted position by the binding action of pins 44. The pins hold the arm 43 firmly, and yet permit sliding adjustment of the arm. In this adjustment as the nozzle approaches alignment with the rigid bases of the flapper unit W member 19 and triangle 20, the proportion relation is reduced and with the nozzle in direct alignment with the mentioned bases, the proportion becomes a one to one relation because the bending of the flapper resilient leg no longer changes the relation between the nozzle and the flapper unit. The device thus becomes a simple on-off action device operated simply by the movement of the flapper unit about the axis 24 in closing or opening the nozzle 26 and consequently operating the pipe line valve 41 only from full on to full off positions, or the reverse.

I claim:

In a pneumatic action device for use in instruments as described, a nozzle, means for producing a pneumatic flow through said nozzle, a flapper unit mounted in the path of said pneu-

matic flow for pivotal movement about an axis with respect to said nozzle so as to vary said flow, said flapper unit including a flexible portion movable independently of said unit movement as another means of varying said flow, means for producing said unit movement in response to changes in a variable condition, a pneumatic relay connected to said nozzle and operable by variations of said flow to produce a relay output force, and a ball piston pneumatic unit arranged to direct said relay output force against said flapper unit flexible portion through ball contact therewith substantially on said flapper unit axis to produce said independent movement in opposition to said unit movement, whereby pivoting of said flapper unit about said axis causes said flexible portion to pivot about said ball without further flexing, and said nozzle and said flapper unit achieve a particular position relation, with said relay output force available as a working force which is proportionally representative of said response to said variable condition change.
